UNITED STATES PATENT OFFICE.

HANS HOLZWARTH, OF MULHEIM-ON-THE-RUHR, GERMANY, ASSIGNOR TO LIGNITE COAL AND BY-PRODUCTS CORPORATION, OF MINNEAPOLIS, MINNESOTA, A CORPORATION OF DELAWARE.

PROCESS AND APPARATUS FOR HEATING ROTARY KILNS.

Application filed March 1, 1922. Serial No. 540,336.

To all whom it may concern:

Be it known that I, HANS HOLZWARTH, a citizen of Germany, resident of Mulheim-on-the-Ruhr, Germany, have invented a certain new and useful Improvement in Processes and Apparatus for Heating Rotary Kilns, of which the following is a specification.

My present invention relates to the heating of rotary kilns, and has been devised particularly for the external heating of rotary kilns serving for the distillation of coal and other bituminous materials. For operations of this character, comparatively low temperatures are employed, and very special requirements must be observed. First of all, the temperature of the kiln wall, throughout the length of the kiln, should be as uniform as possible within the limits of about 450 and 500° centigrade; at no point should the temperature materially exceed 450 to 500°, and especially, care should be taken to avoid any local excessive heating of the kiln wall to red heat. Again, it is desirable that the material under treatment, which owing to the rotation of the kiln assumes an inclined position, should receive as directly as possible the heat issuing from the furnace. Furthermore, the heating itself should be as thorough as possible, that is to say, the gas or other fuel employed for heating the kiln should be burned or consumed as completely as possible.

My invention has been devised for meeting these partly conflicting conditions, and a satisfactory example of a heating device embodying this invention is shown in the accompanying drawings, in which Fig. 1 is a vertical section on line 1—1 of Fig. 2, Fig. 2 is a horizontal section substantially on line 2—2 of Fig. 1, and Fig. 3 is a sectional view similar to Fig. 1, illustrating another form of the heating device.

The furnace proper or combustion chamber *a* is located at a distance from the rotary kiln or drum *b*. This furnace consists of a sort of muffle in which the fuel is consumed at a high temperature in a practically complete manner. The fuel may be solid (coal, semi-coke, lignite, etc.) and used in lumps placed on a grate *a'*, or I may use coal-dust or other powdered fuel, or liquid or gaseous fuel, for which purpose a nozzle *a''* has been

indicated. Both kinds of fuel may be used together. The hot products pass through conduit *c*, the walls of which are very hot or incandescent, so that any unconsumed fuel particles will catch fire when they strike these walls, thus insuring perfect combustion. The conduit *c* is preferably given a shape or direction such as to cause the flame and gaseous current to impinge against the wall, particularly by giving said conduit a descending portion, as indicated in Fig. 2. The conduit *c* is preferably located in a plane perpendicular to the longitudinal axis of the kiln *b* at the central portion of the kiln, and conveys the hot combustion products to the outer surface of said kiln at the lower portion thereof, between the ends of the kiln. The conduit *c* flares as it approaches the kiln, and has inlets *d* to admit cold or moderately preheated air for the purpose of reducing the temperature of the combustion products before they reach the outer surface of the kiln. The mixture of such air with the combustion products is discharged against the (iron) wall of the kiln *b* between two ledges or tongues *e*, *f* of the setting. The tongue *f* extends quite close to the outer surface of the kiln, so that no material portion of the heating mixture can travel directly to the smoke flue or discharge flue *g*, which is separated by the said tongue *f* from the discharge portion of the conduit *c*. This discharge portion preferably consists of two channels *h*, *i* extending in opposite directions along the kiln *b* and contracted outwardly as shown in Fig. 2. These channels communicate with the annular heating chamber *k* which surrounds the rotary kiln and opens into the discharge flue *g*. The kiln *b* should preferably be rotated in the direction indicated by the arrow, so that the heating gases issuing through the channels *h*, *i*, between the ledges or tongues *e*, *f*, will strike the ascending portion of the kiln on which the bulk of the material under treatment rests in an inclined position. The combustion gases produced in the furnace *a* have a temperature of about 1200° centigrade. This temperature is brought down to about 750° centigrade by the air admitted through the inlets *d*. The cooling effect of this air may be regulated by varying its temperature, that is, I may employ

- either cool air, or air preheated to a degree proportioned to the effect to be obtained, but in any event only moderate preheating of the air would be employed. The cooling effect of the air may also be regulated by varying the amount of air admitted, for which purpose the openings or inlets *d* may be adjusted or controlled individually or jointly by valves or dampers of any well-known or approved construction. Any unconsumed fuel particles will be ignited upon striking the highly heated and even incandescent portions of the conduit *c*, and particularly the ledge or tongue *e*.
- 15 The heating mixture, having a temperature of about 750° centigrade, travels lengthwise of the lower portion of the kiln, in the contracting channels *i*, *i* and also around the kiln *b* in the annular chamber *k*, to reach the discharge flue *g*. The wall of the kiln is thus heated to an average temperature of about 450° centigrade, and at the time of leaving the chamber *k*, the gases have cooled down to approximately 450° centigrade.
- 20 25 In order to obtain a better utilization of the heating gases, I may cause them to pass through a heat-exchange apparatus on their way from the heating chamber *k* to the discharge flue *g*, to give up part of their heat to the air which is on its way to the inlets *d*. In this manner the temperature of the gases may be reduced to about 150° centigrade before they enter the discharge flue.
- 25 30 Various modifications may be made without departing from the nature of my invention as set forth in the appended claims.
- I claim:
1. The process of heating rotary kilns for the distillation of coal and other bituminous materials, which consists in producing combustion gases of comparatively high temperature, then mixing them with air of lower temperature, and then bringing the mixture thus cooled into contact with the kiln.
  2. The process of heating rotary kilns for the distillation of coal and other bituminous materials, which consists in producing combustion gases of comparatively high temperature, then mixing them with a gaseous medium of lower temperature, and then bringing the mixture thus cooled into contact with the kiln.
  3. The process of heating rotary kilns for the distillation of coal and other bituminous materials, which consists in producing combustion gases of comparatively high temperature, then mixing them with a fluid of lower temperature, and then bringing the mixture thus cooled into contact with the kiln.
  4. The process of heating rotary kilns for the distillation of coal and other bituminous materials, which consists in producing combustion gases of comparatively high temperature, then mixing them with a fluid of lower temperature to obtain a mixture of about 750° centigrade, and then bringing such mixture into contact with the kiln.
  5. The process of heating rotary kilns for the distillation of coal and other bituminous materials, which consists in producing combustion gases of comparatively high temperature, then mixing them with a fluid of lower temperature to obtain a mixture of about 750° centigrade, then bringing such mixture into contact with the kiln, and thereupon cooling the used mixture to a temperature of about 150° by bringing it into heat-exchange relation to the said fluid while the latter is on its way to be mixed with the combustion gases.
  6. A device for heating rotary kilns, comprising a combustion chamber, a conduit leading therefrom in a plane perpendicular to the longitudinal axis of the kiln, channels extending laterally from said conduit on opposite sides thereof adjacent to the kiln and lengthwise thereof, tongues extending lengthwise of the kiln on opposite sides of said channels, an annular chamber surrounding the kiln and communicating with said channels, and a discharge flue communicating with said annular chamber and extending from a point adjacent to one of said tongues.
  7. A device for heating rotary kilns, comprising a combustion chamber, a conduit leading therefrom in a plane perpendicular to the longitudinal axis of the kiln, channels extending laterally from said conduit on opposite sides thereof adjacent to the kiln and lengthwise thereof, said channels being provided with inlets for a cooling medium.
  8. A device for heating kilns or like structures, comprising a combustion chamber, a conduit leading therefrom toward the central portion of the structure to be heated, spaced tongues extending lengthwise of said structure adjacent thereto, lateral channels located between said tongues and communicating with said conduit, said channels having inlets for a cooling medium, an annular chamber communicating with said channels and extending around said structure, and a discharge flue extending from said annular chamber adjacent to one of said tongues.
  9. A device for heating kilns or like structures, comprising a combustion chamber, a conduit leading therefrom toward the central portion of the structure to be heated, spaced tongues extending lengthwise of said structure adjacent thereto, lateral channels extending in opposite directions from said conduit and contracted away from such conduit, said channels terminating adjacent to said structure between said tongues, and having inlets for a cooling medium, an annular chamber surrounding said structure and communicating with said channels, and a

discharge flue extending from said annular chamber adjacent to one of said tongues.

10. A device for heating rotary kilns, comprising a combustion chamber, a conduit leading therefrom, spaced tongues extending lengthwise of the kiln, one of said tongues extending close to the periphery of the kiln, and the other terminating at a greater distance therefrom, a channel located between 10 said tongues and communicating with said

conduit, an annular chamber surrounding the kiln and communicating with said channel, and a discharge flue extending from said annular chamber adjacent to the first-named tongue, on the side thereof opposite to said channel.

In testimony whereof I have hereunto set my hand.

HANS HOLZWARTH.
